UNITED STATES PATENT OFFICE.

ERIC JULIUS FILELAD, OF LEICESTER, ENGLAND, ASSIGNOR TO IMPERIAL TYPE WRITER COMPANY, LIMITED, OF LEICESTER, ENGLAND.

ROTATABLE CONTACT-BREAKER FOR MAGNETOS AND OTHER PURPOSES.

1,241,273.

Specification of Letters Patent. Patented Sept. 25, 1917.

Application filed March 10, 1917. Serial No. 153,919.

To all whom it may concern:

Be it known that I, ERIC JULIUS PILBLAD, a subject of the King of England, residing at Leicester, in England, have invented certain new and useful Improvements in Rotatable Contact-Breakers for Magnetos and other Purposes, of which the following is a specification.

This invention relates to magneto contact-breaker devices of the type wherein the contacts are carried on a rotating spindle and one contact is connected to the spindle by an arm which bears against a stationary cam whose operative face is shaped to move the arm axially relatively to the spindle to effect the break in the circuit. It is a disadvantage of contact-breakers as at present commonly used, that the surfaces of the contact-points are so difficult of access for inspection, cleaning and adjustment; it is the prime object of the present invention to provide a construction of contact-breaker, such that the working surfaces of the contact-points shall be readily accessible for inspection etc.

According to the present invention, a magneto contact-breaker device of the type described, is characterized by having the arm which carries the movable contact so connected to the spindle that it can be readily moved from its operative position in such a manner as to carry one contact away from in front of the other to render both working faces of the contact readily visible and accessible.

Conveniently, according to this invention, the arm carrying the movable contact is hinged to a part connected with the spindle, and displaceable locking-means are provided for maintaining the arm in the operative position. The locking-means may take the form of a resilient finger which normally constitutes the resilient control for the operative end of the arm, but which is pivotally mounted on the spindle so as to be movable about its pivot to a position where it permits the said operative end to be swung away from the cam.

One embodiment of the present invention is illustrated in the accompanying drawings in which—

Figure 1 is a central vertical longitudinal

section of the complete magneto, but showing the contact-breaker device in elevation;

Fig. 2 is a longitudinal section on the line 2—2 of Fig. 3 to a larger scale than that of Fig. 1 of the parts constituting the contact-breaker device and of some adjacent parts;

Fig. 3 is an end elevation of a detail, and

Fig. 4 is a side elevation of the parts shown in Fig. 3, but with the movable contact swung away for inspection.

The contact-breaker device comprises an inner contact-carrying disk A carried on a tubular spindle B, keyed at B¹ into the spindle C of the magneto armature. Mounted upon the disk A, but electrically insulated from it, is an outer disk D which serves to carry the outer contact, not directly but upon a hinged arm as hereinafter described. The disk D has two lugs D¹, upturned from the general plane of the disk, which support a pivot pin E. Upon the pivot pin E is mounted the arm which carries the outer contact, this arm being in the form of a disk F that is centrally apertured and that is provided with three radial projecting portions. Two of these have their extremities turned down out of the general plane of the disk to constitute lugs at F¹ to engage with the pin E.

On the opposite side to the pivot lug F¹ is a finger-like extension F² to the arm, which carries a fiber wiper G to bear upon the cam. Just at the base of the finger F² is mounted the movable contact H which co-operates with the fixed contact H¹ mounted upon the inner disk A. The aperture in the disk F is shaped in the manner clearly shown in Fig. 3 so as to clear a pillar D³ extending axially from the outer disk D. The aperture is, however, enlarged in the direction away from the finger F², beyond the amount necessary to clear the pillar D³, for reasons which will hereinafter appear.

The outer disk D is cut away along the line D², as seen in Fig. 3, in order to clear the contact H¹.

A piece of plate-spring is provided to form a resilient finger J whose free end has a slight projection J¹ arranged to engage with a corresponding depression in the finger F². The other end of this finger is

pierced to receive the pillar D^3 and is riveted thereon, but so as to be free to rotate upon the pillar about the axis of rotation of the spindle.

5. The cam of the device is seen at K and is formed of a ring of metal that is stamped to give the requisite cam-surface, as will readily be understood from the drawing.

The inner and outer disks A and D are secured together in any convenient manner and the whole device is mounted on the end of the spindle C by the aid of a single central bolt L, registering engagement being provided by the key B¹.

15. In normal operation the disks D and A and the parts carried thereon rotate with the spindle C thus causing the wiper G to cooperate with the stationary cam K to separate the contacts H H¹ periodically in the well-known manner, the spring-finger J serving to keep the contacts closed when the cam permits. It will be readily seen that the oscillations of the arm F take place about the pivot pin E.

25. If now it is desired to inspect or obtain access to the working surfaces of the contacts H H¹ the resilient finger J is swung around the pillar D^3 away from the position shown in Fig. 3 to the position shown in 30 Fig. 4, whereupon the whole arm F can be swung about the pin E into the position shown in Fig. 4 thus moving from its operative position and carrying the contact H away from in front of the contact H¹ so that both working faces of the contact are readily visible and accessible. It will be seen from an inspection of Figs. 3 and 4 that the enlargement, above referred to, to the central aperture of the arm F serves to accommodate the resilient finger J when the parts are moved into the position shown in 40 Fig. 4. The portions of the apparatus to the right of the inner disk A, as viewed in the drawings, do not constitute part of the present invention, but are merely shown to indicate the general disposition of the parts which constitute this invention relatively to parts whose construction is well-known.

What I claim as my invention and desire 50 to secure by Letters Patent is:—

1. In a magneto contact-breaker, the combination of two contact-carrying members simultaneously rotatable about the same axis and whereof one is periodically moved to open the contacts by carrying one of them away from the other in a direction parallel to the said axis of rotation, means to connect the said moved member to the other said member so that the two rotate in unison but so that the said moved member is movable relatively to the other so as to carry the contact upon it away from the other and expose the working faces of both the said contacts simultaneously to view and means nor-

mally to maintain the said moved member 65 in the operative position, substantially as set forth.

2. In a magneto contact-breaker, the combination of two contact-carrying members simultaneously rotatable about the same axis 70 and whereof one is periodically moved to open the contacts by carrying one of them away from the other in a direction parallel to the said axis of rotation, a hinge so to connect the said moved member to the other 75 that the two rotate in unison but the said moved member is movable relatively to the other so as to carry the contact upon it away from the other and expose the working faces of both the said contacts simultaneously to 80 view and means normally to maintain the said moved member in the operative position, substantially as set forth.

3. In a magneto contact-breaker, the combination of two contact-carrying members 85 simultaneously rotatable about the same axis and whereof one is periodically moved to open the contacts by carrying one of them away from the other in a direction parallel to the said axis of rotation, a hinge 90 so to connect the said moved member to the other that the two rotate in unison but the said moved member is movable relatively to the other so as to carry the contact upon it away from the other and expose the working faces of both the said contacts simultaneously to 95 view and displaceable locking-means to maintain the said moved member normally in the operative position, substantially as set forth.

4. In a magneto contact-breaker, the combination of two contact-carrying members simultaneously rotatable about the same axis and whereof one is periodically moved to open the contacts by carrying one of them 105 away from the other in a direction parallel to the said axis of rotation, a hinge so to connect the said moved member to the other that the two rotate in unison but so that the said moved member is movable relatively to the other so as to carry the contact upon it 110 away from the other and expose the working faces of both the said contacts simultaneously to view, and a resilient finger constituting the resilient control normally to 115 hold the contacts closed supported from the said other member to be pivotally movable relatively thereto about the said axis of rotation from its normal position to one in which it permits the said moved member to be swung away from the other about the said hinge, substantially as set forth.

5. In a magneto contact-breaker, the combination of two contact-carrying members simultaneously rotatable about the same axis 120 and whereof one is periodically moved to open the contacts by carrying one of them away from the other in a direction parallel

to the said axis of rotation, a hinge by which the said moved member is so connected to the other as to be movable about an axis transverse to the axis of rotation, and an axial support connected to the said other member and extending through a clearance aperture in the said moved member and provided with a resilient finger which normally bears upon the said moved member but is pivotally movable upon said support to free the moved member, substantially as set forth.

In testimony whereof I have signed my name to this specification in the presence of two subscribing witnesses.

ERIC JULIUS PILBLAD.
